DESIGN FOR AN APPLIQUÉ OR SIMILAR ARTICLE

Henry Dreyfuss, New York, N. Y., assignor to American Export Airlines, Inc., New York, N. Y., a corporation of Delaware

Application May 13, 1939, Serial No. 84,972

Term of patent 14 years

To all whom it may concern:

Be it known that I, Henry Dreyfuss, a citizen of the United States and a resident of New York, county of New York, and State of New York, have invented a new, original, and ornamental Design for an Applique or Similar Article, of which the following is a specification, reference being had to the accompanying drawing, forming a part thereof, in which the figure is a face view of an applique or similar article illustrating my new design. The article has no appreciable thickness.

I claim:

The ornamental design for an applique, or similar article, substantially as shown and described.

HENRY DREYFUSS.
